UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,294,111.

Specification of Letters Patent. Patented Feb. 11, 1919.

Application filed January 2, 1918. Serial No. 209,971.

To all whom it may concern:

Be it known that I, CHARLES W. KECKLER, a citizen of the United States, residing at Newark, in the county of Essex, State of 5 New Jersey, have invented certain new and useful Improvements in Telephone-Exchange Systems, of which the following is a full, clear, concise, and exact description.

This invention relates to telephone exchange systems and more particularly to 10 those in which the operator's telephone sets are connected to the usual link or connecting circuits by means of operator-controlled listening keys.

15 In such systems, it is desirable to prevent the operator from listening in on established connections.

It is the object of this invention to provide a simple and inexpensive system of this 20 character in which the operator is absolutely prevented from simultaneously listening to the conversations being communicated over two or more of the telephone lines.

In accordance with a feature of this invention, the listening keys of the link or connecting circuits assigned to an operator are so interconnected that the operator's telephone set is rendered ineffective upon 25 any attempt being made to contemporaneously connect the operator's telephone set 30 with two or more subscriber's lines.

This and other features not specifically mentioned, will more fully appear from the following description and the annexed drawings illustrating one embodiment of the invention.

In the accompanying drawing, the figure 40 shows two ordinary subscribers' lines A and B terminating at a central office at which several link or connecting circuits C, D and E, having listening keys 10, 20 and 30, respectively, are provided for interconnecting such lines. For the sake of clearness, only such portions of the connecting circuits are 45 shown as are essential to a complete understanding of the invention and although only the listening keys and their associated connections are shown for cord circuits C and E, it may be assumed that such circuits are 50 similar to the one shown for cord circuit D.

The bus or common conductors 4 and 5 connected with the operator's telephone circuit are multiplied at each of the keys 10, 20 and 30 and connection with any link circuit 55 may be established by the closure of

the normally open contacts 11 and 17, 21 and 27 or 31 and 37 of the associated listening key. The normally closed contacts 14, 24 and 34 of the listening keys 10, 20 and 30, respectively, are connected *in seriatim* by 60 means of conductors 7 and 6, thereby forming a normally continuous common conductor joining all of the listening keys.

It is thought that the invention may be more fully understood from the following 65 description of the operation of the system.

Assuming that the subscriber at line A desires to converse with the subscriber on line B, the signal of line A is displayed in the usual manner and the operator inserts plug 70 1 of cord circuit D in the jack of line A and actuates listening key 20. The actuation of this key connects the operator's telephone set conductors 4 and 5 with the tip and ring conductors respectively, of the answering 75 portion of the cord circuit D by the closure of contacts 21 and 27. At the same time, the tip conductor of the cord circuit is opened at contact 22 of key 20 and the calling end of the cord circuit D is short-circuited by means of a connection from the tip of the cord through contacts 26 and 27 to the ring of the cord. After ascertaining 80 that a connection with line B is desired, the operator inserts plug 2 in the jack of line B 85 and restores the listening key 20 so that subscribers A and B may then converse after subscriber B has been signaled in the usual manner.

It will be noted, however, that in case 90 listening key 20 is actuated at any time the calling end of the cord circuit is short-circuited as before, thus preventing the operator from listening in on the conversation conducted over that cord circuit. 95

In case the operator should actuate key 10 of the cord circuit C before key 20 is restored, the bus conductors 4 and 5 will be short-circuited by a circuit extending from conductor 4 through contact 23 of key 20, 100 conductor 7, contacts 15 and 16 of key 10 to conductor 5. Thus the operator will be unable to listen in on either cord circuit C or D without restoring either key 10 or key 20. 105

If the listening key 30 of cord circuit E is operated, instead of key 10, prior to the restoration of key 20, the conductors 4 and 5 will be short-circuited over a circuit extending from conductor 5, contacts 26 and 25 of 110

key 20, conductor 6, contact 33 of key 30 to conductor 4.

It will be evident that no manipulation of the cord circuits and their associated apparatus will enable the operator to simultaneously listen to conversations on two or more of the lines.

What is claimed is:

1. A telephone exchange system comprising a plurality of telephone lines terminating at a central office, a plurality of link circuits for interconnecting the lines, an operator's telephone set, a listening key for each link circuit for connecting the operator's telephone set therewith, a normally closed contact for each key, a plurality of additional contacts for each key, and a common circuit conductor interconnecting the normally closed contacts and coöperating with the additional contacts to short-circuit the operator's telephone set when two of the listening keys are actuated.

2. A telephone exchange system comprising a plurality of telephone lines terminating at a central office, a plurality of link circuits for interconnecting the lines, an operator's telephone set, a listening key for each link circuit for connecting the operator's telephone set therewith, a common conductor interconnecting the keys, means associated with each listening key for interrupting the common conductor, and additional means associated with the listening keys and coöperating with the interrupting means to short-circuit the operator's telephone circuit when any two of the keys are actuated.

3. A telephone exchange system comprising a plurality of telephone lines terminating at a central office, a plurality of link circuits for interconnecting the lines, an operator's telephone set, a listening key

for each link circuit for connecting the operator's telephone set therewith, a common conductor interconnecting the keys, means associated with the listening keys to sectionalize the portion of the common conductor connecting any two of the keys upon the operation of said two keys, and additional means associated with said two keys and coöperating with said section of common conductor to short-circuit the operator's telephone set.

4. A telephone exchange system comprising a plurality of telephone lines terminating at a central office, a plurality of link circuits for interconnecting the lines, an operator's telephone set, a listening key for each link circuit for connecting the operator's set therewith, and means for preventing the contemporaneous connection of the telephone set with a plurality of the link circuits, said means consisting of a short circuit for the telephone set established solely by the coöperation of contacts of the listening keys and circuit connections therefor.

5. A telephone exchange system comprising a plurality of telephone lines terminating at a central office, a plurality of link circuits for interconnecting the lines, an operator's telephone set, a listening key for each link circuit for connecting the operator's set therewith, and means for preventing the operator from simultaneously listening in on a plurality of the link circuits, said means consisting of a short circuit for the operator's set established solely by the operation of contacts on the keys and circuit interconnections therefor.

In witness whereof, I hereunto subscribe my name this 28th day of December A. D. 1917.

CHARLES W. KECKLER.
